Marque Buchanan, Inventor.

UNITED STATES PATENT OFFICE.

MARQUE BUCHANAN, OF WINDSOR, ILLINOIS, ASSIGNOR OF ONE-THIRD TO
JOHN BAXTER, OF FAIRLAND, ILLINOIS.

SWING-RAIL FROG.

SPECIFICATION forming part of Letters Patent No. 637,229, dated November 21, 1899.

Application filed May 13, 1899. Serial No. 716,698. (No model.)

To all whom it may concern.

Be it known that I, MARQUE BUCHANAN, a citizen of the United States, residing at Windsor, in the county of Shelby and State of Illinois, have invented a new and useful Swing-Rail Frog, of which the following is a specification.

My invention relates to improvements in railway-switches in which a springless-frog construction is employed to simplify and cheapen the device, enable the parts of the switch to be applied directly to ordinary tie-plates, and to promote the safety of the switch by rendering the parts positive in their adjustment and service.

A further object is to provide means by which the movable point or swing-rails may be positively adjusted to vary the distance between the free ends of said rails and thereby compensate for the wear which takes place on the frog and the swing-rails.

With these ends in view the invention consists in the novel construction and arrangement of parts, which will be hereinafter fully described and claimed.

In the drawings, Figure 1 is a plan view showing the switch adjusted for the main line and indicating by dotted lines the position of the swing-rails when adjusted for a train to pass to the siding. Fig. 2 is a vertical cross-section on the plane indicated by the dotted line 2 2 of Fig. 1. Fig. 3 is an enlarged detail view of the adjustable connection between the swing-rails, the plane of the section being indicated by the line 3 3 of Fig. 1. Fig. 4 is a detail view of a part of the connecting-rod for the swing-rails, showing a slot to provide for the relative longitudinal movement of said rails.

The same numerals of reference are used to indicate like and corresponding parts in each of the several figures of the drawings.

The rail 5 of the main track is solid, continuous, or unbroken at the railway-crossing, while the other main-track rail has its two members or parts 6 6^a separated a proper distance at the crossing to accommodate one of the pair of swing-rails employed at the intersection of the main-track rail 6 with one member 9 of the divided side-track rail, as will

presently appear. The side-track rail 8 is substantially continuous or unbroken, and it is disposed in the ordinary relation usual to railway-switches at the crossing of the tracks. The other rail of the side track has its members 9 9^a divided or separated to accommodate the other swing-rail of the improved switch construction, and the rails 6 9 of the main and side tracks are disposed to join with the frog 7, as clearly shown by Fig. 1. 55

As indicated briefly by the preceding description, my improved switch embraces a pair of swing-rails, which are aligned with the members 6^a 9^a of the main track and side track, respectively, and these swing-rails are 60 coupled together for simultaneous adjustment, in order that they may be alternately adjusted to contact with the opposite faces of the frog 7. One rail of the pair of swing-rails is indicated by the numeral 10, and it 70 spans the space between the side-track rail 9^a and the frog 7, and the end of said rail 10 which joins the section 9^a is spliced or pivotally connected thereto, so that the opposite or free end of the rail 10 may move laterally 75 for a limited distance with respect to one side or face of the frog 7. This free end of the swing-rail 10 has its inner face beveled or inclined at 11 to fit snugly to the side of the frog 7 when the rail 10 is adjusted to align 80 with the rail members 9 9^a to close the side track. The other member 12 of the pair of swing-rails used in my switch is arranged alongside of the rail 10 to span the space between the rail member 6^a of the side track 85 and the frog 7, and the end of said rail 12 which is contiguous to the rail member 6^a is spliced or otherwise connected to said rail member 6^a for the free end of the swing-rail 12 to lap against the opposite side or face of 90 the frog 7 from the side which is engaged by the free end of the swing-rail 10. The free end of said swing-rail 12 is beveled or inclined at 13 to adapt said rail 12 for fitting snugly against the frog 7. The pointed end of the 95 frog and the beveled ends of the swing-rails 10 12 are seated on tie-plates 14 of ordinary construction and which are fastened to the ties 15 by any approved means; but while the frog 7 occupies a stationary position it is evi- 100

dent that the swing-rails 10 12 must play or move on the tie-plates in order to open or close the main line or the siding.

The free ends of the swing-rails 10 12 are coupled or united together in their proper spaced relation by means of the binders 18 19, which are disposed on the lower sides of the rails and in the intervals between the ties and the plates 14 thereon, so that the binders 10 may move or travel with the rails 10 12 without interference from the permanent fixed parts of the switch. These binders are of the usual or any preferred construction well known to those skilled in the art, and, as is 15 ordinary, said binders are constructed to embrace the flanged feet of the swing-rails in order that they may be held thereon by keys or other adjustable devices.

Any suitable means may be provided for 20 throwing the swing-rails 10 12; but in the simple embodiment of the invention shown by the drawings I employ a bell-crank lever 20, which is fulcrumed on one of the ties or to a plate fixed thereon, and to one arm of this 25 lever is pivoted an operating-rod 21, which extends to the switch-stand or the signal-tower. This bell-crank lever is connected with the coupled swing-rails 10 12 by a single pitman having adjustable connection with 30 both of said rails in order that the two rails may be operated simultaneously from the bell-crank lever, and said rails may be adjusted relatively to each other for varying the space or distance between the free beveled 35 ends of said swing-rails in order to compensate for the wear which takes place on the point of the frog and the pointed ends of the rails, thereby insuring nicety and accuracy in the fitting of the swing-rails to the frog 40 and also overcoming any gapping between said rails and the frog. One end of this pitman 23 is threaded for a part of its length, as at 24, and is passed through an aperture or slot 26 in the swing-rail 12. A pair of clamp- 45 ing-nuts 27 are screwed on the threaded part 24 of the pitman in positions to bind against opposite sides of the rail 12, and thereby make said rail and pitman fast one with the other.

50 On the threaded extremity of the pitman 23 is screwed a forked or bifurcated coupling-head 28, adapted to be removed when the nuts 27 are to be screwed on the threaded part 24 of the pitman, thus providing for the ready assemblage of the elements and the easy disconnection of the parts in the event of renewal of or repairs to the switch mechanism. The pitman 23 has a threaded link 29 fitted in the bifurcated head 28, and this link 55 and the pitman-head are connected pivotally or slidably together by means of a pin or bolt 30, which passes through a slot in the forked head and one end of said link to provide for the proper movement of the rails. The 60 threaded link is extended through a slot or aperture 31, which is provided in the swing-rail 10, and said link and rail are made fast

together by the employment of nuts 32, which are screwed on the link in position to embrace the respective sides of the swing-rail 70 10. It will be noted that the binders 18 19 serve to adjustably couple the flanged feet of the two swing-rails, and the link 29 also couples the pitman adjustably to the swing-rails, whereby the rails 10 12 may be adjusted laterally to vary the interval or space between the free ends thereof. This adjustment of the rails serves to take up the wear on the frog 7 and the beveled end of the rails, and the described construction wholly obviates the employment of a spring and at the same time insures the swing-rails having the proper intimate engagement with the frog to prevent gapping of the switch mechanism at the crossing between the main and side tracks. 80 85

By reference to Fig. 1 it will be noted that the full lines indicate the swing-rail 12 as engaging with the left-hand face of the frog 7, so as to make the rail 12 constitute a continuation of the broken main-line rails 6 6^a, 90 and the switch is thus adjusted to permit a train to pass along the maintrack. The bell-crank 20 may be thrown to its reversed position (shown by dotted lines in Fig. 1) to pull the pitman 23 in a direction to shift the relation 95 of the rails 10 12 to the frog, as shown by dotted lines, and thus the rail 10 is engaged with the frog, while the rail 12 is disengaged therefrom to make the rail 10 span the space between the members 9 9^a of the side track, 100 whereby a train may pass from the main track to the side track or vice versa.

From the foregoing description it will be seen that I have provided an improved switch construction which wholly dispenses with the 105 use of springs and enables the elements of the switch to be fitted to ordinary tie-plates, thus simplifying the construction and promoting the convenience in the installation of the switch. The swing-rails are actuated 110 positively, and they are confined securely in place against accidental movement, thus contributing to the security of the track.

If it is considered necessary to have the frog locked, I may employ a facing-point lock 115 and the switching-movement lock and detector-bars, such as are used in the familiar type of interlocking plants. It will be noted that the swing-rails are spliced to the main-track and siding rails, and the frog is also 120 spliced to said rails, as in the common construction.

Changes in the form, proportion, size, and the minor details of construction within the 125 scope of the appended claims may be resorted to without departing from the spirit or sacrificing any of the advantages of this invention.

Having thus described the invention, what I claim is—

1. In a railway-switch, the combination with a main track, a side track, and a frog, of the pair of swing-rails operatively connected with divided rails forming parts of

the main and side tracks and having their free ends beveled to embrace the respective sides of the frog, adjustable devices connecting the free beveled ends of the swing-rails 5 and spacing the same laterally with relation one to the other, and a pitman connected with said rails to simultaneously move the same, substantially as described.

2. In a railway-switch, the combination 10 with a main track, a side track, and a frog, of the swing-rails in operative relation to certain rails of the main and side tracks, and a pitman rigidly coupled to the swing-rails, the joint between the pitman and the rails permitting adjustment of the two rails laterally 15 with respect to one another to compensate for wear of the pointed ends of the swing-rails and the frog, substantially as described.

3. In a railway-switch, the combination 20 with a frog and a pair of swing-rails, of a

pitman connected fast to one of the swing-rails, and a link pivoted to said pitman and adjustably connected to the other swing-rail, substantially as described.

4. In a railway-switch, the combination 25 with a frog, and a pair of spaced swing-rails, of a pitman having a threaded end made fast adjustably to one of said rails, a forked head detachably secured to said pitman, and a link having an adjustable connection with the 30 other swing-rail and pivoted to the forked head, substantially as described.

In testimony that I claim the foregoing as my own I have hereto affixed my signature in the presence of two witnesses.

MARQUE BUCHANAN.
